UNITED STATES PATENT OFFICE

139,860

DESIGN FOR AN AIRPLANE

Othmar F. Maycen, New York, N. Y.

Application October 15, 1942, Serial No. 108,547

Term of patent 14 years

(Cl. D71—1)

To all whom it may concern:

Be it known that I, Othmar F. Maycen, a citizen of the United States, residing in the Borough and county of Bronx, city and State of New York, have invented a new, original, and ornamental Design for an Airplane, of which the following is a specification, reference being had to the accompanying drawings, forming a part thereof, in which

Figure 1 is a plan view of the subject airplane showing my new design;

Figure 2 is a front elevational view of the airplane depicted in Figure 1;

Figure 3 is a side elevational view of the airplane depicted in Figure 2; and

Figure 4 is a top perspective view of the airplane as it would appear in flight.

I claim:

The ornamental design for an airplane, substantially as shown.

OTHMAR F. MAYCEN.
